(57) **CLAIM**

The ornamental design for a seat furniture, as shown and as described.

DESCRIPTION

FIG. 1 is a front perspective view of a seating furniture, showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear perspective view thereof.

The cross-hatching shading in the figures is fragmentarily shown for convenience of illustration, it being understood that the cross-hatching is uniformly continued over the surface on which it appears.

The broken lines in the figures are for the purpose of illustrating portions of the seating furniture that form no part of the claimed design.
